Patented Sept. 17, 1957

181,027

TELEVISION ANTENNA

Roger Mark Singer, New York, N. Y., assignor to Snyder Manufacturing Company, Philadelphia, Pa., a corporation of Pennsylvania

Application December 6, 1956, Serial No. 44,081

Term of patent 3½ years

(Cl. D26—14)

Fig. 1 is a front perspective view of a television antenna showing my new design with the antenna arms in divergent position;

Fig. 2 is a rear elevational view thereof with the antenna arms in an upright position;

Fig. 3 is a side elevational view thereof;

Fig. 4 is a fragmentary front elevational view; and

Fig. 5 is a side elevational view thereof to a reduced scale.

The dot-dash line showing of a television set in Fig. 5 is for illustrative purposes only.

I claim:

The ornamental design for a television antenna, as shown and described.
